WARDROBE SUITCASE HAVING PIVOTAL FRAME FOR MOUNTING GARMENT-HANGER SUPPORTING BARS

Maurice P. Koch, San Francisco, Calif.

Application December 7, 1946, Serial No. 714,742

2 Claims. (Cl. 190—41)

1

My invention relates to wardrobe suitcases, and fixtures for the same.

An object of this invention is to provide a suitcase of light construction but somewhat longer than the ordinary suitcases, in which a number of garments may be packed on hangers supported on a pivoted frame without wrinkling the same.

Another object of this invention is to provide a pivoted frame within a suitcase adapted to carry a number of garment hangers upon which the garments may be hung and folded over bars on said frame, so as to be packed in a comparatively narrow space without wrinkling.

Another object of this invention is to provide a frame within said suitcase which frame has means for adjustably carrying garment hangers so as to accommodate garments of various lengths or to space garments in desired order.

Another object of this invention is to provide a frame within said suitcase which frame has a plurality of spaced engagement means on the longitudinal members thereof adapted to receive the ends of adjustable cross-members for carrying garment hangers thereon.

In this specification, and the annexed drawings, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

With the foregoing and other objects in view, which will be made manifest in the following detailed description, reference is had to the accompanying drawings for the illustrative embodiment of the invention, wherein:

Fig. 1 is a perspective view of the open suitcase.

Fig. 2 is a side view of an adjustable cross-bar, some parts being shown in section.

Fig. 3 is a plan view of the adjustable cross-bar, some parts being shown in section.

Fig. 4 is a plan view of the garment hanger attaching means on the cross-bar.

Fig. 5 is a front view of the suitcase showing the garment supporting frame swung into the cover and holding a plurality of garments, the body of the suitcase being shown in section.

Fig. 6 is a front view of the suitcase showing a modified garment supporting frame swung into the cover and holding a plurality of garments, the body of the suitcase being shown in section.

Fig. 7 is a cross-section taken along the line 7—7 of Fig. 5; and

Fig. 8 is a fragmentary perspective view of the frame showing the adjustable cross-bar.

5 In carrying out my invention I make use of a wardrobe suitcase which has a body section 1 and a cover section 2, suitably hinged at 3 where the narrow sides 5 and 6 of said sections 1 and 2 meet respectively. This suitcase is preferably of substantially full wardrobe length, but of light construction, so that it may be carried in hand by its handle 8, on one side of said body section 1. Usual locks 10 are also provided on said suitcase to lock the sections together.

10 Within the cover section 2 there is provided a swingable garment supporting frame 12 consisting of two parallel longitudinal side beams 13 and 14 connected by a cross-piece 15 at the end adjacent the hinged sides 5 and 6. The free ends of said beams 13 and 14 are connected by a cross-rod 17, the ends of which protrude slightly beyond said beams. When the frame 12 is swung, for the purpose of packing, out of the cover section 2 over and into the body section 1, the ends of the cross-rod 17 rest on lugs 18 attached to the inner surfaces of the side walls 19 and 20 of said body section 1.

15 The frame 12 is further strengthened by a plurality of parallel transverse braces 22 which extend from the beam 13 to the beam 14, and which are attached to the front sides of said beams as shown in Figs. 5, 6 and 7. The braces 22 are spaced from each other and are intended to support the garments while the same are being put on the frame and when said frame rests in the cover section 2.

20 From the hinged ends of the beams 13 and 14 extend arms 24 which arms 24 are pivoted to the cover section 2 as shown at 25. The arms 24 are preferably connected by a brace 26.

25 In the beams 13 and 14 are pairs of opposed and spaced slots 27 of uniform size. The slots 27 are adapted to hold the ends of adjustable cross-bars 29. Each cross-bar 29 consists of a flat bar 30 one end of which is bent into a hook 31. The other end of said bar carries a spring 32 thereon and is inserted into a sleeve 34 slideable over said bar. The sleeve 34 has a rim 35 bent toward said bar 30 to enclose said spring 32. The bar 30 terminates with an abutment 36 to confine the spring 32 between said abutment and the bent rim 35 of the sleeve 34. The sleeve 34 is attached by a pin 38 to the hub of a hook 39 which is substantially of the same 30 shape and size as the hook 31. The spring 32

provides extensible connection between the hook 39 and the bar 38 and permits said cross-bar 29 to be attached to the frame 12 at any desired place by inserting the hook 31 into one of the slots 27 in the beam 14, pulling the hook 39 outwardly and placing the end of the latter into the opposite slot 27 in the beam 13. The spring 32 pulls the hook 39 into said slot and securely holds the same therein.

The cross-bar 29 is provided with a lock knob 41 by which a suitable garment hanger 42 is held on the cross-bar. The hanger 42 in this illustration comprises a straight rod 44, the ends of which are bent to form shoulder portions 45 at the apex of which is arranged a square flat plate 47 having an inverted T-shaped slot 48 therein. The slot 48 is passed over the knob 41 whereupon said knob is turned a quarter of a turn for the purpose of locking said hanger to the cross-bar 29, as shown in Fig. 4.

The cross-bar 29 may also be used to keep the garments securely in place. Fig. 5 shows a plurality of spaced cross-bars 29 with the hangers 42 attached, each of which hangers carries a garment 50. The top-most garment 50 is wrapped around the cross-rod 17 and the end of said garment is held in place by the top cross-bar 29.

A plurality of the hangers 42 may be retained on a bracket 52 attached to the middle of the top cross-piece 15 at right angles to the plane of the frame 12. The bracket 52 has guiding and retaining means for stacking said hangers 42 thereon. In the herein illustration the bracket 52 is made in the form of an angular loop, one end of which is secured to the middle of the cross-piece 15. The other end 53 is slotted so as to fit the inverted T-slot 48 of the hangers. A retainer side 54 and the back side 55 connects said ends of the bracket 52. The plate 47 of the hangers 42 are slid over the end 53 of the bracket 42 and are retained by the retainer side 54 of said bracket. The hanger 42 has a hook 56 pivoted to the plate 47 by means of which said hanger may be suspended on a bar, or any other support outside the suitcase.

The frame 12 is shown in Fig. 1 in packing position in which the free end of said frame rests on the lugs 18. To pack said frame, coats, jackets, and the like, are first hung on a hanger 42 retained by the bracket 52. Their ends may be wrapped around one of the braces 22 if desired. Then one of the cross-bars 29 is secured to the frame 12 by inserting the hooks 31 and 39 into a pair of opposed slots 27 and a hanger 42 carrying one or more garments is attached to said cross-bar. Other cross-bars 29 are attached to said frame 12 and the hangers 42 with the garments thereon are fastened to said bars. If desired one or more cross-bars 29 may be used for the support of the garments carried by said hangers. As shown in Fig. 5 the garment supporting frame 12 may be packed in a different manner by attaching in close proximity to the cross-rod 17, one of the cross-bars 29 to the under side of the beams 13 and 14, instead of the top side of the same as shown in Fig. 1. The hanger 42 with the garments thereon is thereupon attached to said cross-bar 29, and the loose ends of said garments may be wrapped around the cross-rod 17 and secured in their position by one of the cross-bars 29. Another cross-bar 29 is then attached to said beams between the first mentioned cross-bar 29 and the bracket 52 and a hanger 42 is attached thereto. The garments supported by the latter

hanger are placed on the first mentioned garments. Then a hanger 42 with the garments thereon is slid on the bracket 52. The latter garments are placed on the previously packed garments. One or more cross-bars 29 are used to hold the garments in place by attaching the same to the top side of the beams 13 and 14.

When the garments have been packed the frame 12 is swung into the cover section 2 of the 10 wardrobe suitcase wherein the protruding ends of the cross-rod 17 are caught and securely retained by suitable spring catchers 58.

The garments can be easily removed from the pack and stored. The packing is compact and 15 smooth and is entirely within one section only of the wardrobe suitcase, and no garment overhangs into the other section. The entire wardrobe suitcase is comparatively light, is easily carried and can be speedily packed and unpacked.

20 The same hangers can also be used for the usual hanging of garments outside of the wardrobe suitcase by turning the hanger hooks 180 degrees, yet a comparatively large number of such hangers with garments thereon can be conveniently packed on the frame and in the wardrobe suitcase herein described. The garments are confined within the cover section, thus leaving the entire body section of the wardrobe suitcase for packing other articles therein. Fig. 6 shows a 25 modified form of my invention wherein the frame 12' consists of two beams 60 and 61 so arranged that their wide surfaces 62 are parallel to the bottom, or the top, of the wardrobe suitcase, depending upon the position of the frame in said case. The beams 60 and 61 are provided with spaced pairs of opposed slots 63 cut at right angles to said surfaces 62. The slots 63 admit the bent ends 65 of the extensible cross-bars 29.

The frame 12' is packed in the same manner 30 as the frame 12 and is normally retained in the cover section 2 of the wardrobe suitcase leaving the body section for other articles.

I claim:

1. A wardrobe suitcase comprising a body section, a cover section, and a garment supporting frame extending substantially the entire length of the cover section and being fulcrumed adjacent an end of the cover section; said frame including a pair of spaced parallel side bars; means 45 for connecting the same; each of said side bars having a plurality of spaced slots therein; extensible cross-bars, the ends of said cross-bars having means to fit into said slots selectively from either side of the frame; and means on the cross-bars for holding garment hangers thereon.

2. A wardrobe suitcase comprising an elongated body section, an elongated cover section, and an elongated garment supporting frame pivoted to one end of the cover section, so as to be swingable into and out of said cover section; said frame including two parallel side members; a plurality of transverse braces affixed to said side members and connecting the same; a plurality of adjustable cross-bars; means for detachably connecting said cross-bars to said side members, said means including hooks on the ends of each cross-bar offset to one side of a plane containing the cross-bar and engaging said side members selectively from either side of the frame, thereby positioning said cross-bar out of the plane of said frame on the respective selected side of said frame, and means on said cross-bars for holding garment hangers thereon.
